UNITED STATES PATENT OFFICE

144,811

DESIGN FOR A COMBINATION PORTABLE LAVATORY

William L. Smith, Horsham, Pa.

Application November 6, 1945, Serial No. 123,506

Term of patent 14 years

(Cl. D4—4)

To all whom it may concern:

Be it known that I, William L. Smith, a citizen of the United States, residing at Horsham, in the county of Montgomery and State of Pennsylvania, have invented a new, original, and ornamental Design for a Combination Portable Lavatory, of which the following is a specification, reference being had to the accompanying drawings consisting of four sheets of five figures, numbered Figs. 1 to 5 inclusive, forming a part thereof.

Fig. 1 is a front view of the combination portable lavatory showing my new design with the cabinet closed;

Fig. 2 is a front view of the combination portable lavatory showing my new design with the

cabinet open and the washbowl in closed position;

Fig. 3 is a front view of the combination portable lavatory showing my new design with the cabinet open and the washbowl in open position;

Fig. 4 is a side view of the combination portable lavatory of Fig. 2 with the right hand wall of the cabinet removed; and

Fig. 5 is a side view of the combination portable lavatory of Fig. 3 with the right hand wall of the cabinet removed.

I claim:

The ornamental design for a combination portable lavatory, as shown.

WILLIAM L. SMITH.
